UNITED STATES PATENT OFFICE

THOMAS E. TAYLOR, OF MANSFIELD, OHIO, ASSIGNOR TO THE TAPPAN STOVE COMPANY, OF MANSFIELD, OHIO, A CORPORATION OF OHIO

TOP FRAME AND GRID CONSTRUCTION FOR OPEN TOP GAS RANGES

Application filed February 24, 1930. Serial No. 430,555.

This invention relates generally to gas ranges and more particularly to gas ranges of the open top type having a frame or key plate which is disposed over the top burners.

5 One of the objects of the invention is to provide a top frame or key plate which is so constructed and arranged as to reduce dissipation of heat to a minimum.

Another object of the invention is to provide a top frame or key plate for ranges of the character described which is provided with a plurality of grids which are disposed over the burners respectively, so as to provide a receptacle support; and in which each of the grids is made up of a plurality of sections which are spaced apart and independently supported on the frame whereby to reduce dissipation of heat by conduction.

Another object of the invention is to provide a range of the character described having a top frame having a plurality of grids thereon which are disposed over the burners respectively, and in which each of the burners is provided with an air plate which is supported over the burners and so constructed and arranged as to direct the secondary air for supporting combustion into the bases of the flame jets and to prevent flow of air up and around a receptacle supported on the grid.

A still further object of the invention is to provide a top frame for gas ranges of the character described which is simple in construction and well adapted for quantity production at a comparatively low cost.

Further and more limited objects of the invention will appear as the description proceeds and by reference to the accompanying drawings in which Fig. 1 is a fragmentary top plan view of a gas range having a top frame constructed in accordance with the preferred embodiment of my invention;

Fig. 2 is a fragmentary plan view of one section of the frame;

Fig. 3 is a fragmentary view partly in vertical section and partly in elevation disclosing a portion of the top frame with a burner arranged therebeneath together with the air plate supported on the burner; and Fig. 4 is 50 a fragmentary vertical sectional view illus-

trating the relative position of the air plate and burner nozzles. Referring now to the drawings, reference character 1 designates the top of an open top gas range having a top frame or key plate 55 which is made up of a pair of sections 2 and 3 which are supported on shoulders 4, 5, 6 and 7 provided on the top portion of the stove. Each of the sections of the top frame is provided with a pair of receptacle supporting 60 grids 8 and 9, and 10 and 11 which are preferably substantially rectangular in shape and cast integral with the frame sections. Each of the grids is formed in two sections which are spaced apart and connected with the frame by means of arms 12, 13, 14 and 15, which are preferably cast integral with the frame and grids. Each of the grids also 65 comprises radially disposed arms 16 spaced apart and arranged as shown most clearly 70 in Figs. 1 and 2. Disposed below the grids respectively are burners 17. Each of the burners comprises a plurality of radially disposed rows of gas orifices 18 which are disposed between the arms 16 as shown most 75 clearly in Fig. 1. Secured over each of the burners 17 is an air plate 19 having a plurality of radially disposed slots therein through which the nozzles on the burners project.

The air plate 19 with the slots arranged there- 80 in as shown directs the secondary air into the base portions of the flame jets and serves to provide a more efficient combustion. The burner nozzles project through the air plate as shown most clearly in Fig. 1. The air plate 85 also prevents a stream of air from flowing up around a kettle or receptacle supported on the grid, thus absorbing the heat of combustion. This air plate materially increases the efficiency of the flame and is particularly 90 desirable when the fuel used is a gas such as propane.

It will be seen that each of the grids is made up of a pair of sections which are spaced apart and that each grid is connected with the 95 frame at only four points. This arrangement reduces dissipation of heat from the burner by conduction through the arms of the grids and thus materially increases the efficiency of the range. In order to strengthen 100

the grids and add rigidity to the top frame; the adjacent grid sections are connected with each other by arms 20 which are preferably cast integral with the frame sections. The 6 burners disclosed are of standard construction and are supplied with gas through a manifold 21. The supply of gas to each of the burners is controlled by valves 22, 23, 24 and 25. The valve 26 controls the supply of 10 gas to the oven burner (not shown).

Various changes may be made in the details of construction as well as in the manner of constructing and assembling the various parts without departing from the spirit of my 15 invention. The embodiment of my invention herein disclosed is illustrative only and is not to be considered in a limiting sense. It is therefore to be understood that the invention is limited only in accordance with the scope 20 of the appended claims.

Having thus described my invention, what I claim is:

1. In a gas range, the combination of a frame, a burner disposed below said frame, a 25 grid disposed over said burner and supported from said frame at no more than four spaced points, said grid being made up of a plurality of sections which are spaced apart and independently supported on the frame 30 whereby to reduce dissipation of heat by conduction.

2. In an open top range, the combination of a plurality of burners, a frame over said 35 burners and consisting of a pair of sections, each section having a pair of grids disposed above said burners respectively, each of said grids having means securing the same to said frame at equi-spaced points whereby to reduce dissipation of heat.

40 3. In an open top range, the combination of a plurality of burners, a frame disposed above said burners and having a plurality of grid portions extending over said burners respectively, means securing said grids to 45 said frame at no more than four spaced points whereby to reduce dissipation of heat, each grid being made up of a pair of sections spaced apart and independently supported on said frame.

50 4. In an open top gas range, the combination of a plurality of gas burners supported within the upper portion of the range, a frame extending over the burners and consisting of a pair of sections each of which is 55 provided with grids which are disposed over said burners respectively, each grid consisting of a plurality of arms shaped to provide a receptacle support, and having a plurality 60 of separate sections, and means independently connecting each of said sections with said frame at a plurality of spaced points, said means comprising lugs which are so spaced and so connected with the frame and 65 grid sections as to reduce materially the dis-

sipation of heat away from the burner by conduction.

5. In an open top gas range, the combination of a plurality of gas burners supported within the upper portion of the range, a frame extending over the burners and consisting of a pair of sections each of which is provided with grids which are disposed over said burners respectively, each grid consisting of a plurality of arms shaped to provide 70 a receptacle support, and having separate sections which are spaced apart and independently supported on said frame whereby to reduce heat dissipation, each of said grids being substantially rectangular in shape, an air plate disposed below each of said grids and having a plurality of slots therein disposed in alignment with the gas orifices in the 75 burner.

6. In an open top gas range, the combination of a plurality of burners, frames disposed above said burners and having a plurality of grid portions disposed over said burners respectively and forming receptacle supports, each receptacle support consisting of a plurality of separate sections which are independently secured to said frame at spaced points, a plurality of lugs connecting said receptacle support with said frame, said lugs being so spaced and disposed as to materially reduce the conduction of heat away from said burners by said receptacle supports, each receptacle support including a plurality of radially disposed arms disposed 90 between the gas orifices of the burners. 100

In testimony whereof, I hereunto affix my signature.

THOMAS E. TAYLOR.
